UNITED STATES PATENT OFFICE.

FREDERICK A. ZIELKE, OF MILWAUKEE, WISCONSIN.

MERRY-GO-ROUND.

Application filed March 23, 1923. Serial No. 627,023.

To all whom it may concern:

Be it known that I, FREDERICK A. ZIELKE, a citizen of the United States, and resident of Milwaukee, in the county of Milwaukee, and State of Wisconsin, have invented certain new and useful Improvements in Merry-Go-Rounds; and I do hereby declare that the following is a full, clear, and exact description thereof.

10 This invention relates to toys.

Objects of this invention are to provide a toy merry-go-round which may be easily operated by means of a string, which will rewind the string by virtue of the momentum 15 of the revolving parts, and which is equipped with miniature horses, swinging or flying seats, and other parts corresponding to a real merry-go-round.

Further objects are to provide a toy merry-go-round which may be cheaply produced, 20 which is of simple and sturdy design, and which may be packed in a relatively small space for shipping or handling.

An embodiment of the invention is shown 25 in the accompanying drawings, in which:—

Figure 1 is a perspective view of the apparatus.

Figure 2 is a fragmentary sectional view of a portion thereof.

30 The device comprises a base 1 of any suitable material, having a substantially centrally arranged boss 2, and within this boss the conical end 3 of a vertical spindle 4 is revolvably socketed. An inverted U-shaped support 5 has its feet 6 secured to the base in any suitable manner and is provided with 35 an upper transverse portion 7 through which the spindle 4 loosely passes.

The upper portion of the spindle carries 40 a pair of outwardly projecting arms 8 which may, if desired, be formed of a single piece of material forced through an opening through the spindle 7 and may terminate in ornamental balls or knobs 9. Swinging seats

45 10 are supported by means of cords, or other suitable members, from eyelets 12 carried by the rod 8. If desired a second rod 13 may be passed through the spindle at a point intermediate its ends and may be provided 50 with downwardly extending portions 14. Miniature horses 15, or any other desired devices, may be carried by the lower portion of the arms 14, as indicated in Figure 1. The upper end of the spindle 4 may

carry a flag staff 16 from which a flag 17 55 extends, if desired.

The means for rotating the spindle may comprise a cord 18 which has one of its ends passed through a hole 19 in the spindle 4 and secured in any desired manner. The 60 cord is initially wound, as shown in the drawings, and is left in this position with its free end 20 extending outwardly a sufficient distance to allow it to be freely grasped by the operator.

65 The operation of the device is as follows: The operator grasps the free end 20 of the cord and pulls it outwardly, thereby unwinding the cord from the spindle and causing the spindle to rapidly rotate. This 70 causes the seats 10 to swing outwardly like the seats in a circle swing, for instance. After the cord has been unwound it is relieved of tension and the momentum of the 75 parts causes it to rewind upon the spindle in the reverse direction.

It will be understood, therefore, that an extremely simple means has been provided whereby a miniature merry-go-round may be freely and easily operated by an unskilled 80 person so as to cause repeated rotations of the merry-go-round, first in one direction and then in the other.

It will further be seen that an attractive 85 toy of simple and sturdy construction has been provided, and that such toy may be readily dismantled by withdrawing the spindle from the support and may, therefore, be packed in a small space, greatly facilitating handling and shipping. The 90 corners of the base 1 may, as shown in Figure 1, be marked with the numerals 1, 2, 3 and 4. By numbering the corners, as indicated, the toy may be utilized as a game; that is, when the reel is spun in either 95 direction, parties may pick out a horse, or a chair, and the figure which stops over the highest number would thus win.

I claim:—

A toy merry-go-round comprising a base, 100 a U-shaped support having outwardly turned feet secured to said base and having an apertured upper transverse portion, a vertical spindle revolvably socketed in said base and extending through the aperture in said 105 transverse portion and projecting thereabove, a rod extending transversely through the upper portion of said spindle and pro-

jecting outwardly therefrom, swinging seats suspended from the outer portions of said rod, and a cord secured to the lower portion of said spindle between said base and the transverse portion of said support, said cord being adapted to be wound about said spindle and withdrawn therefrom, whereby

the momentum of said parts will cause the rewinding of said cord.

In testimony that I claim the foregoing I 10 have hereunto set my hand at Milwaukee in the county of Milwaukee and State of Wisconsin.

FREDERICK A. ZIELKE.
